UNITED STATES PATENT OFFICE.

GARDNER L. CONLEY, OF CHICAGO, ILLINOIS, ASSIGNOR TO STANDARD OIL COMPANY, OF WHITING, INDIANA, A CORPORATION OF INDIANA.

DESIGN FOR A CANDLE.

Application filed February 1, 1923. Serial No. 5,041. Term of patent 14 years.

To all whom it may concern:

Be it known that I, GARDNER L. CONLEY, a citizen of the United States, residing at Chicago, county of Cook, and State of Illinois, have invented a new, original, and ornamental Design for a Candle, of which the following is a specification, reference being had to the accompanying drawing, forming a part hereof, in which—

I claim:

The ornamental design for a candle as shown.

GARDNER L. CONLEY.
